UNITED STATES PATENT OFFICE

100,680

DESIGN FOR A COMBINATION LIP STICK HOLDER AND MIRROR

Edward L. Anderson, Attleboro, Mass., assignor to Ripley and Gowen Company, Incorporated, Attleboro, Mass.

Application June 26, 1936, Serial No. 63,521

Term of patent 3½ years

To all whom it may concern:

Be it known that I, Edward L. Anderson, a citizen of the United States, residing at Attleboro, in the county of Bristol and State of Massachusetts, have invented a new, original, and ornamental Design for a Combination Lipstick Holder and Mirror, of which the following is a specification, reference being had to the accompanying drawing, forming part thereof.

tion lipstick holder and mirror showing my new design.

I claim:

The ornamental design for a combination lipstick holder and mirror, as shown.

EDWARD L. ANDERSON.
